UNITED STATES PATENT OFFICE.

JOHN L. BROMLEY, OF OIL CITY, PENNSYLVANIA, ASSIGNOR TO OIL CITY GAS ENGINE STARTER COMPANY, A CORPORATION OF PENNSYLVANIA.

GAS-ENGINE VALVE.

No. 831,598.

Specification of Letters Patent.

Patented Sept. 25, 1906.

Application filed April 5, 1905. Serial No. 253,938.

To all whom it may concern:

Be it known that I, JOHN L. BROMLEY, a citizen of the United States, residing at Oil City, in the county of Venango and State of Pennsylvania, have invented new and useful improvements in Gas - Engine Valves, of which the following is a specification.

This invention relates to valves of the puppet type designed especially for use in connection with gas or other explosive engines, and has for its objects to produce a comparatively simple inexpensive device of this character in which the strength of the spring employed for closing the exhaust may be reduced for obviating the hammering of the valve upon its seat together with consequent wear upon the parts, one in which a double bearing will be accorded for the valves, thus insuring positive and accurate seating of the latter, and one wherein return of the expelled gases to the combustion-chamber is wholly obviated, thereby insuring a fresh charge being received for each explosion.

A further object of the invention is to provide a device of this character having in its organization a pair of reversely - movable valves and a main seating-spring common to and tending to seat both valves, one wherein each valve will be guided in its movements by the stem of the other and one wherein an auxiliary spring assists in opening the inlet and firmly seating the exhaust-valve.

With these and other objects in view the invention comprises the novel features of construction and combination of parts more fully hereinafter described.

In the accompanying drawings, Figure 1 is a sectional view of parts of an explosive-engine equipped with a valve embodying the invention. Fig. 2 is a sectional elevation of the valve shown on an enlarged scale.

Referring to the drawings, 1 designates a valve-casing having an inlet-port 2 and an exhaust-port 3, said ports being adapted for communication with a passage or duct 4, leading to the engine-cylinder 4'. Arranged for normally closing communication between the port 2 and passage 4 is an inlet-valve 5, having a tubular stem 6, closed at its outer end and slidably disposed within the casing 1, which latter is provided with a seat 7, upon which the valve normally rests. For normally closing communication between the exhaust-port 3 and passage 4 is a valve 8,

slidably disposed in the casing and designed to normally rest upon a seat 9, provided in the latter, said valve being carried by a stem 10, extending upon opposite sides of the valve and having a bearing at the outer side of the latter in the casing 1 and at the inner side of the valve in the tubular stem 6, with which the stem 10 is slidably and telescopically engaged, as shown herein. Formed upon the inner end of the stem 10 is a reduced portion or seat 11, which receives one end of a primary seating-spring 12, housed within the tubular stem 6 and having bearing at its other end upon the closed end of the latter, there being formed in the casing 1 a recess 13, in which is disposed an auxiliary spring 14, bearing at one end upon the valve 5 and at its other end on the end wall of the recess. The stem 10, which extends rearwardly, is slidably mounted in a bearing 15 on the cylinder and provided at its rear end with a roller 16, adapted to contact with an eccentric head 17, journaled upon a suitable stub-shaft 18 and connected by a gear 19 and pinion for operation from the engine-shaft 21, it being understood that during the operation of the device the head 17 will be driven from the shaft 21 and act upon the stem 10 for opening the valve 8 at suitable intervals.

In practice the normally expanded spring 12, owing to its arrangement between the valve-stems, acts reversely upon the latter, thereby tending to maintain both of the valves in seated position, as will be readily understood, while the spring 14 has a tendency to unseat the valve 5 and at the same time to force the valve 8 more firmly upon its seat 9. It will be understood that in action when a charge is drawn through the port 2 under the action of the engine-piston within its cylinder the valve 5 will through suction aided by the spring 14 be moved bodily from its seat in the usual manner, thus permitting the charge to enter the cylinder through the medium of the passage 4. The spring 14 during this action serves as an auxiliary aid to the main seating-spring 12 for forcing the valve 8 more firmly upon its seat, and thus obviating liability of the latter valve opening while the charge is being taken into the cylinder. After each explosion the stem 10 is acted upon mechanically in manner above described for unseating the valve 8 to permit exhaust of the gases and other products of

the explosion through the port 3, it being apparent that while the valve 8 is open the spring 12 will be compressed and maintain the valve 5 firmly upon its seat.

5 From the foregoing it is apparent that I produce a simple inexpensive device adapted for the attainment of the ends in view, one wherein the valves will move smoothly and evenly and be actuated in their movements 10 one by the other, one in which accurate seating of the valve is insured and pounding of the valve 8 upon its seat with consequent wear of the parts obviated, and one wherein opening of the valve 8 and return of the expelled gases during the taking of a fresh 15 charge into the cylinder is positively prevented. In attaining these ends it is to be understood that minor changes in the details herein set forth may be resorted to without 20 departing from the spirit or scope of the invention.

Having thus fully described the invention, what is claimed as new is—

1. In a device of the class described, a casting provided with valve-seats, a pair of reversely-movable valves designed to rest respectively on said seats, a primary spring common to and acting upon both valves to

maintain the latter in seated position, and an auxiliary spring acting upon and tending to unseat one of the valves. 30

2. In a device of the class described, a casting provided with a pair of valve-seats, a pair of valves designed to rest respectively on said seats, stems provided on the valves and arranged in telescopic sliding engagement, a primary spring common to and acting upon both valves to maintain the latter in seated position, and an auxiliary spring acting upon and tending to unseat one of the valves. 35 40

3. In a device of the class described, a casting provided with a pair of valve-seats and having a recess in rear of one of said seats, a pair of reversely-movable valves designed to rest respectively on said seats, a primary spring common to and acting on both valves for maintaining them in seated position, and a second spring disposed in said recess and tending to unseat the adjacent valve and move the other valve to seated position. 45 50

In testimony whereof I affix my signature in presence of two witnesses.

JOHN L. BROMLEY.
